UNITED STATES PATENT OFFICE.

THEODOR HÜGO, OF WILMERSDORF, NEAR BERLIN, GERMANY.

MACHINE FOR GUMMING ENVELOPES, PAPER BAGS, AND THE LIKE.

Application filed February 23, 1924, Serial No. 694,723, and in Germany November 20, 1922.

The invention relates to an improvement in machines for gumming envelopes, paper-bags, and the like.

In known machines of this kind employing a gumming-stamp which is connected with a sliding member adapted to travel with a reciprocating motion along horizontal guides, between a gum-feed roller and the paper to be treated, it is necessary to provide means for lowering and raising the gumming-stamp at the end of its travel. It has hitherto been the practice to connect the gumming stamp rigidly with the sliding member, so that considerable power was required to raise the stamp owing to the weight of the relatively heavy sliding member which must also be raised at the same time. This considerably decreases the effective speed at which the machine can be worked conveniently without submitting the component parts to undue shocks and strains.

According to the present invention, a means is provided which permits the gumming-stamp to be raised and lowered independently of the sliding member, whilst still carried to and fro by said sliding member in the course of the reciprocatory horizontal motion of the member, so that it is possible for the gumming-stamp to be raised and lowered when required without any corresponding movement of the sliding member. The force necessary to raise the gumming-stamp is thereby considerably decreased, and the machine can be worked at a greatly increased speed compared with known machines of this kind.

The invention is illustrated in the accompanying drawings, in which:—

Fig. 1 is a side elevation partly in section.

Fig. 2 is a front elevation partly in section, and

Fig. 3 is a plan of the machine.

a is the horizontally reciprocating sliding member, carrying the gumming-stamp b and actuated by the connecting rods c' and the crank arms c, which are secured at their lower ends to a rock shaft c² carried on the base plate i and provided at one end with a toothed sector c⁸ by which it is geared through the gear train c⁵ to the spindle or shaft d' of the gum-feed cylinder d. The sliding member a having side sleeves a' which are mounted and slidably movable on guide rods f carried by supporting rails g

mounted on the base plate i through the medium of uprights or brackets h.

The supporting rails g have a cross plate k connected to one end of each, said plate being provided at or near its center with a hinge connection or knuckles l and having therebetween a single knuckle or eye m', the knuckles l and m' being held in association by a pivot pin l' extending therethrough, as clearly shown by Fig. 3. The hinge knuckle or eye m' is formed at one end of a lifter bar or guide rail m and whereby the said bar or rail may be vertically oscillated within certain limits to vary the angle thereof on its pivot or hinge connection. To the end of the lifter bar or rail m opposite that pivoted or hinged to the plate k an actuating lever o is pivotally connected and has at the outer end thereof suitable operating means o', which may be connected to any device adapted to vertically reciprocate the same and in turn raise and lower the outer end of the lever o. The lever o is intermediately fulcrumed at n on a fulcrum upright n' supported adjacent to and by the terminal of one of the supporting rails g, and by this means the lifter bar or guide rail m may be also elevated and depressed at its free extremity to effect the operation desired. The lifter bar or guide rail m has the inner end of the lever o connected thereto by a link r, which is movably attached to the free end of the lifter bar or rail m.

The gumming stamp b, which may be of any approved form, has oppositely disposed uprights q secured thereto and slidably movable through vertical sleeves q' held by the adjacent extremity of the sliding member a. The upper ends of the uprights or vertically reciprocating rods q are connected by a cross piece t to the intermediate portion of which is secured a depending bracket t' having a stub shaft or spindle p' extending transversely from the lower end thereof and provided with an anti-frictional roller p, which is held in engagement with the upper surface of the lifter bar or guide rail m. The roller p is free to travel over the lifter bar or guide rail m, and the uprights or vertically reciprocating rods q are free to move in the sleeves q' which are secured to the sliding member a as heretofore specified. Two retractile or retention springs u are secured to the opposite ends of the cross piece t and to the base plate i,

the said springs serving as cushioning means for the gumming stamp or pad *b*, and the elevation of the said stamp or pad through the operation of the lifter bar or rail *m* will be against the tension of the said springs, and when the lifter bar or rail is lowered, the springs will assist in the lowering operation and depression of the stamp. In addition, the springs *u* give to the gum stamp or pad *b* the necessary yielding action relatively to the paper bags or envelopes or other articles *s* disposed under the stamp to receive the gum or adhesive material and illustrated in position in Fig. 1. The machine also includes a gum-holding receptacle or trough *e* in which is mounted the supply or feeding roller *d*. The shaft *c*² is adapted to be driven by any suitable mechanism and the attachment as a whole may be placed in convenient adjacency or association with other mechanism from which the envelopes, bags or other similar articles may be supplied.

By a suitable movement of the lever *o* the guide rail *m* can be raised, thereby raising the roller *p* and consequently the gumming-stamp *b* without any corresponding displacement of the sliding member *a*. Two tension springs *u*, arranged on each side of the machine and secured at their lower ends to the base plate *i* and at their upper ends to the cross piece *t*, serve to depress the stamp *b* when the guide rail *m* is lowered, and also to provide the pressure necessary for the gumming operation when the gumming-stamp *b* is applied to the paper *s* to be gummed.

In operating the machine, the gumming stamp *b* is brought over the paper *s* and, by depressing the guide rail *m* by a suitable and easily regulated movement of the lever *o*, is lowered onto the paper and pressed there firmly by the springs *u*, whereby the gum is transferred to the paper. The stamp *b* is then raised by a suitable movement of the lever *o* and shifted over into engagement with the gum roller or cylinder *d* by the actuation of the sliding member *a* through the medium of the connecting rods *c*', crank arms *c* and rock shaft *c*², the gumming stamp or pad *b* being held elevated until it passes rearwardly over the roller or cylinder *d* and again returns to its forward operating position, when the said stamp or pad is again lowered to engage the parts of the envelope, bags or the like to which it applies the gum or adhesive material.

I claim:

1. In a device of the class specified, the combination with an adhesive substance supply means having a feed cylinder operatively mounted therein, of a longitudinally movable slide having side sleeves, side guides on which the said sleeves have free sliding movement, a rock shaft provided with cranks

and arms connected to the slide, a liquid-transmitting stamping device held by and movable with the horizontally reciprocating slide and also movable vertically without affecting the longitudinal movement of the slide, and means having a vertically movable hinge device for vertically reciprocating the said liquid-transmitting stamping device, the liquid-transmitting stamping device by the means specified being first moved a short distance vertically to evenly spread the liquid on the device to which the said liquid has been applied.

2. In a gumming attachment for envelopes and the like the combination with a liquid gum holding receptacle having a rotatable feed cylinder therein, a frame provided with guides, a slide having opposite side portions thereof engaging the guides and reciprocable horizontally along the said guides, a rock shaft with arms and crank devices connected to and operating the said slide, a gum-transmitting stamping device held by and movable horizontally with the slide, means for effecting a vertical reciprocation of the said stamping device while the latter is moving with the slide, a guide rail hinged at one end and engaging a portion of the means for effecting a vertical reciprocation of the stamping device, and mechanism for operating the latter means and raising and lowering the said guide rail.

3. In a gumming attachment for envelopes and the like, the combination with a liquid gum holding receptacle having a rotatable feed cylinder therein, a frame provided with guides, a slide having opposite side portions thereof engaging the guides and reciprocable horizontally along the said guides, a rock shaft with arms and crank devices connected to and operating the said slide, a gum-transmitting stamping device held by and movable horizontally with the slide, means for effecting a vertical reciprocation of the said stamping device while the latter is moving with the slide, a guide rail hinged at one end and engaging a portion of the means for effecting a vertical reciprocation of the stamping device, the means for effecting a vertical reciprocation of the stamping device including a roller movable on the guide rail, and mechanism for operating the means for effecting a vertical reciprocation of the stamping device and raising and lowering the said guide rail.

4. In an attachment of the class specified, the combination with a trough for holding adhesive material and having a feed or supply roller disposed therein, of a horizontally disposed reciprocating slide member carrying upright devices, a stamping device movable over and in contact with the said roller and having means for engaging the said upright devices to effect a vertical reciprocation of the stamping device without af-

fecting the longitudinal sliding movement of the slide member, a rail hinged at one end for engaging a portion of the said means of the stamping device to raise and lower the latter at proper intervals without modifying the reciprocation of the sliding member or disengaging the same from its hori-

zontal position, and mechanism for operating the said means for effecting a vertical reciprocation of the said stamping device. 10

In testimony whereof I have affixed my signature.

THEODOR HÜGO.
